POCKET CONTAINER

William E. Hoeflin, St. Louis, Mo.

Application June 28, 1954, Serial No. 439,595

7 Claims. (Cl. 150—5)

The invention relates to a device comprising a combination of relatively stiff, but distortable, material, such as one or more sheets of pressboard, and a binding therefor consisting of relatively rough, pliable material secured to the stiff sheet by its inherent adhesive qualities or by pressure or heat, an example of such material being generally known as pressure-sensitive industrial cloth.

A preferred embodiment of the invention consists of a holder, such as is commonly used for pens and pencils, and is usually inserted in the pocket in a coat or vest or other article of clothing, although it may be carried in a brief case, purse, or bag, or pocket secretary.

The objects of the invention are to protect the clothing or the carrier of the user from undue bulging or from being snagged by the articles inserted in the holder; to protect the clothing or other carrier from ink, pencil marks, puncture, etc.; and to facilitate the insertion and removal of articles carried in the pockets.

In the accompanying drawings which illustrate selected embodiments of the invention,

Figure 1 is a front view of an assembly comprising an outer case and an inner receptacle supplied with pen and pencil.

Figure 2 is a vertical section taken on the line 2—2 of Figure 1.

Figure 3 is a horizontal section taken on the line 3—3 of Figure 1.

Figure 4 is a front view of the receptacle removed from the case.

Figure 5 is a front view of a modified structure comprising a wallet with a currency positioning insert unit.

Figure 6 is a front elevation of the unit indicated in Figure 5, removed from the wallet.

In Figures 1—4, A represents a case which may be formed of attractive and relatively expensive leather sheets 1, 2, stitched together at 3 in the usual manner to form a rectangular pocket with three sides of its periphery secured together, the fourth or upper side being open.

Slidably and snugly fitting within case A is a receptacle B, consisting mainly of two overlying, quadrilateral sheets 4, 5 of relatively stiff, but distortable, smooth-surface material, such as pressboard. Strips 6 of relatively thin, pliable material, such as pressure-sensitive industrial cloth or gummed fabric, are applied to the upright marginal portions of sheets 4 and 5, each strip overlying the corresponding contiguous edges of the sheets and adhering to the sheets by the innate characteristics of the strips and securing the sheets together by such adherence and without requiring any stitching, glue, staples, or other securing means which might tend to increase the bulk of the receptacle along its edges or to render the sheets less susceptible of being distorted throughout their width. A similar binding strip 7 is applied to the lower marginal portions and edges of sheet 4 and 5 and forms a bottom for the receptacle.

To facilitate the insertion of pens, pencils, etc., as indicated at C, D, the sheets 4 and 5 are preferably distorted so that they are bowed horizontally and vertically,

2

as best indicated in Figures 2 and 3. This distortion may be effected by shaping the sheets with a forming die or by notching the lower margin of each sheet as indicated at 8 and bringing the edges of the notch together as at 8a before applying strip 7 and, if necessary, applying an extra reinforcing binding strip 9 to the sheets while they are held distorted.

Individual binding strips 10 are applied to the upper edge of each sheet 4, 5, being folded over the sheet edge, thus protecting the edge of the sheet from being nicked by the clips L of the pens and pencils.

With this construction, a pen, pencil, etc., may be readily inserted within the receptacle B and will be retained by its contact with the rough finished, pressure-sensitive binding 10, irrespective of clips L, although the latter may be readily slipped over the individual receptacle sheet and top binding strip. The receptacle will be retained in the outer case A by its snug fit therein and by the friction between the side binding strips 6 and the inner face of the case.

The user may be a salesman or auditor having a set of pens and pencils which he may want to carry in his pocket or have ready for use on his desk. If so, he may remove the receptacle and lay it on the desk where it serves as a convenient pen and pencil holder so that the pens and pencils may be kept conveniently together and yet quickly replaced as a group in the case and in the user's pocket. When a pen is to be inserted in the receptacle, the bowed contour of the latter, as indicated in Figure 3, will facilitate the insertion of the end of the pen or pencil into the receptacle or, if the receptacle is not initially bowed, its sheets may be readily distorted away from each other by pressure applied by the thumb or finger at opposite edges.

In this respect, the relatively stiff sheets function differently from the usual case made of substitute leather, which is likely to double over in a fold, if pressure is applied to opposite edges, instead of gaping open to receive the pen or pencil.

The pocket container shown in Figures 5 and 6 comprises an outer case K, which may be formed in the usual manner and of choice leather, and is provided with small pockets 20 for cards, etc., and with one or more pockets 21 for currency, indicated at R, which is folded over a sheet 22 of relatively stiff, but deformable, material, to the edges of which are applied binding strips 23 of pressure-sensitive, industrial cloth, as previously described, which restrain the sheet 22, and the currency folded thereover, from slipping out of case K.

With this arrangement, the currency may be folded over the insert to form a flat unit which may be inserted into the case, thus avoiding the inconvenience and risk of opening the entire wallet in order to insert a bill unfolded, as is a common practice.

The combination of the relatively stiff, but deformable, smooth-surface sheets and the relatively pliable, inherently adherent binding strips, may be incorporated in various devices, such as change cases, comb cases, card cases, key cases, memorandum cases, etc., and other materials may be used for those described, such as body sheets of thin metal, cardboard, plastics, and binding strips of rough-surface fabric having adhesive applied to one face for securing the same to the smooth-surface body sheets. To further restrain the device from slipping out of a garment pocket, a part 24 of a snap fastener may be affixed to the outside of the device and positioned to be gripped by a mating fastener 25 secured to the garment G.

The details of the construction may be varied otherwise than as shown without departing from the spirit of the invention and the exclusive use of those modifications coming within the scope of the invention is contemplated.

What is claimed is:

1. A receptacle for insertion in a clothing pocket or the like, comprising two sheets of relatively smooth-surface, stiff material, opposing one another with corresponding edges adjacent to each other, and a binding for said sheets consisting of a strip of relatively pliable, rough material covering a plurality of contiguous edges of said sheets and folded over the adjacent marginal portions of said sheets and securing said sheets together and adapted to resist sliding of the receptacle over the material of a pocket into which the receptacle is inserted, at least one pair of contiguous edges being exposed and providing for insertion of an object between the sheets.

2. A receptacle of the class described, comprising a pair of super-imposed, quadrilateral sheets of relatively stiff, but distortable, smooth-surface material, and a binding of relatively thin, pliable, rough-surface material overlying and adhering to at least two of the contiguous marginal portions of said sheets and forming the sole means for securing said sheets to each other, said binding being applied to other marginal portions of each of said sheets individually, but leaving said latter-mentioned marginal portions free of each other to be spaced apart for the insertion of objects between the sheets.

3. A receptacle of the class described, comprising a pair of super-imposed, quadrilateral sheets of relatively stiff, but distortable, smooth-surface material, and a binding of relatively thin, pliable, rough-surface material applied to three of the marginal portions of one of said sheets and extending over the adjacent edges of both sheets and then folded back over the corresponding marginal portions of the other sheet, the sheets being bendable away from each other along the fourth marginal portion of each sheet to accommodate the insertion of objects between the sheets.

4. A receptacle for insertion in a clothing pocket or the like, comprising a plurality of rectangular sheets of stiff, but bendable, pressboard, lying flat against each other with corresponding edges contiguous to each other, and a relatively narrow binding consisting of a strip of pressure-sensitive, industrial cloth embracing the marginal portions of said sheets along two parallel edges and one connecting edge and securing said sheets together throughout the major portion of the periphery of the contiguous edges, there being a substantial extent of said periphery exposed to accommodate insertion of an object between the sheets.

5. A receptacle of the class described comprising a

pair of quadrilateral sheets of stiff, but distortable, pressboard overlying each other, with their edges contiguous, and contacting with each other, the sheets being bowed between two spaced apart opposite edges of the pair of sheets, a relatively narrow binding strip of pressure-sensitive, industrial cloth folded over the contiguous edges of said sheets at said opposite edges and over the contiguous edges at one end of the pair of sheets connecting said first mentioned two edges and overlying the adjacent marginal portions of the sheets to secure the sheets together and to resist their slippage over the material of a pocket into which the receptacle is inserted, the margins of the sheets along said connecting edges united by the binding being notched to permit the ready distortion of the portions of the sheets spaced from said end to accommodate the insertion of objects between the sheets.

6. A receptacle of the class described comprising two sheets of relatively stiff, but distortable, material overlying each other with their edges substantially super-imposed, the sheets having V-shaped notches extending inwardly from one pair of said superimposed edges, binding of readily pliable material applied to the marginal portions of said sheets adjacent to said pair of edges and covering said notches and folded over the corresponding edges and forming a closed bottom of the receptacle, and similar binding extending along the marginal portions of the sheets extending angularly from said first-mentioned portions and folded over the corresponding edges and forming closed sides of the receptacle.

7. A receptacle as described in claim 6, in which a separate pliable, thin, rough-surface, binding strip is applied to the fourth marginal portion of each sheet individually to protect the corresponding edge and resist slippage of the receptacle over the material of a pocket or the like into which it may be inserted.
